SHARPENING STONE OILER AND SUPPORT

William A. Kuhlman, Los Angeles, Calif.

Application November 12, 1938, Serial No. 240,054

9 Claims. (Cl. 51—213)

My invention relates to a sharpening stone oiler and support and has for its principal object, to provide a relatively simple, practical and inexpensive receptacle that serves as a container for a sharpening stone or stones with a body of oil in which the stone or stones are submerged while not in use and, said receptacle also serving as a support for holding the stone in elevated position while in use.

10 Further objects of my invention are, to provide a skeleton frame that receives and holds in proper assembled relation two sharpening stones which may be of different degrees of texture, for instance, one fine and the other coarse, 15 further, to mount on the ends of said frame pivoted or hinged members that function as handles and supports for the stone carrying frame and further, to construct the ends of the receptacle so that the handles or supporting members 20 may be applied thereto in different positions, so as to maintain the stones within the receptacle entirely submerged in the oil therein or, to hold the stones elevated within said receptacle in order that the tools to be sharpened may be conveniently rubbed on the upper surface of the 25 upper stone.

A further object of my invention is, to provide simple and efficient means for lubricating both members of a duplex sharpening element 30 and, to provide simple and effective means for reversibly associating same with a receptacle that functions as a container for the liquid lubricant that provides a bath for both sharpening stones and has a housing for said sharpening stones 35 while the same are not in use.

With the foregoing and other objects in view, my invention consists in certain novel features of construction and arrangement of parts that will be hereinafter more fully described and 40 claimed and illustrated in the accompanying drawing in which:

Fig. 1 is a top plan view of a sharpening stone oiler and support constructed in accordance with my invention, with a portion of the cover broken 45 away.

Fig. 2 is an enlarged vertical section taken on the line 2—2 of Fig. 1.

Fig. 3 is a vertical section taken lengthwise through the end portion of the housing and showing the duplex sharpening stone suspended in 50 elevated position in order to bring the upper one of the stones into position for use.

Fig. 4 is a plan view of one end of the device and showing the duplex sharpening stones in 55 elevated position.

Fig. 5 is a cross section taken on the line 5—5 of Fig. 4.

Fig. 6 is a detail cross section taken on the line 6—6 of Fig. 4.

Referring by numerals to the accompanying drawing, 10 designates an elongated rectangular container which may be formed from sheet metal and applied to the underside of said container adjacent its ends are transverse strips 11 which may be of rubber, fiber, or other material, that 10 will produce a certain amount of friction to anchor the container when the same is placed on a smooth surface.

The upper portions of the side walls of the container are bent inwardly and downwardly to 15 form inclined flanges 12 that serve to prevent the liquid lubricant within the container from splashing upwardly adjacent the side walls thereof and then running down the outer faces of said side walls. A cover 13 formed of sheet metal 20 serves as a closure for the open upper end of the container.

The upper portions of the end walls of the container extend a short distance above the plane occupied by the upper edges of the side walls and 25 the central portions of the upper edges of said end walls are cut away to form openings 14, the upper edges of which curve downwardly from both ends toward their centers and the corners of the material forming the end walls just above 30 the ends of these openings 14 are cut away to form notches 15.

The distance between the vertical edges of the notches 15 is slightly greater than the distance between the ends of the openings 14.

35

A sharpening stone supporting frame is composed of pairs of side rails 16, preferably strips of metal L-shape in cross section, with the horizontal flange of one rail lying directly on top of the horizontal flange of the other rail and these 40 two sets of rails are tied together at both ends and at one or more intermediate points by transversely disposed bolts or screws 17.

The frame thus constructed serves as a support for a pair of sharpening stones 18 which 45 stones are positioned between and clamped by the vertical flanges of the pairs of rails 16. The thickness of these flanges is substantially greater than the width of the flanges that clamp the sides of said stones.

50

The sharpening stones may be natural oil stones or they may comprise homogeneous blocks of pulverized or powdered abrasive substance, such as emery or carborundum, the particles of which are bonded to each other by means of a 55.

moisture proof adhesive and the two stones have different characteristics, that is, one stone may be formed from fine particles of abrasive substance and the other stone formed from coarser particles of abrasive substance.

Substantially T-shaped members 19, each formed from a single piece of sheet metal provide handles for lifting and reversing the position of the sharpening stones and said members also 10 serving as hooks for suspending the stones within the container 10. The inner end of the central member of each combined handle and hook is provided with a loop 20 that receives one of the end bolts 17 and the connection between these 15 parts is such as to enable the combined handle and hook to swing freely on the bolt. The outer ends of the members 19 terminate in hooks 21 that are adapted to engage over the upper ends of the end walls 10 of the container when the 20 sharpening stones occupy their lowermost position within said container as illustrated in Fig. 2.

The width of each member 19 is slightly less than the space between the vertical edges of the notches 15 in the upper portions of the end walls 25 and, formed in the sides of each member 19 adjacent the loop 20 on the inner end thereof are notches 22. The distance between the inner ends of the notches 22 is slightly less than the distance between the ends of the opening 14 in 30 the end wall.

As a result of the construction just described, the members 19 may be used as handles to lift the sharpening stones from their lowermost position in the container, so as to position the uppermost one of said sharpening stones above the top of the container 10 and wholly above the body of oil within said container and to maintain the stones in this position, the members 19 are swung outward and downward and manipulated 40 so that the notches 22 engage the portions of the end walls of the container just beyond the ends of the openings 14 as illustrated in Figs. 3, 4, and 6, and thus the sharpening stones will be firmly held in their elevated position.

45 To reverse the position of the sharpening stones or turn the same upside down, the members 19 are engaged and the stones lifted entirely out of the container and after being reversed in position, said stones are returned to the container. The curving of the lower edges of the openings 14 facilitates this reversing of the sharpening stones and during such reversing action the bottom edge of one of the notches 22 rides on the curved lower edge of said opening 14.

50 While not in use, both sharpening stones occupy their lowermost position within the container and when so positioned, both stones are entirely submerged in the body of oil within said container. While thus submerged, the stones are suspended by the members 19 with one hook 21 of each pair positioned in the space between the notches 15, thus providing a firm and substantial suspension means for the stones and their frame.

55 By completely submerging both stones in oil while said stones are not in use, practically all particles of metal removed from the tools that are being sharpened on the stones will be dislodged from the stones and passed by gravity to 60 the bottom of the container.

To enhance this dislodgement of the particles of metal from the stones, the same should be manipulated after use so that the stone last used occupies a position in the lower portion of the 65 container and, thus the particles of metal will

as a result of the lubricating action of the oil drop from the stone onto the bottom of the container.

Thus it will be seen that I have provided a sharpening stone oiler and support that is relatively simple in construction, inexpensive of manufacture and very effective in performing the functions for which it is intended.

It will be understood that minor changes in the size, form and construction of the various 10 parts of my improved sharpening stone oiler and support, may be made and substituted for those herein shown and described, without departing from the spirit of my invention, the scope of which is set forth in the appended claims. 15

I claim as my invention:

1. A sharpening stone oiler and support comprising a container, a frame, a sharpening stone carried by said frame and combined handles and hangers hinged on horizontal axes to the ends of 20 said frame and adapted to engage and suspend the frame and the stone carried thereby from the ends of the container.

2. A sharpening stone oiler and support comprising a container, a frame, a pair of sharpening stones carried by said frame and combined handles and hangers hinged on horizontal axes to the ends of said frame for lifting and manipulating said frame and the stones carried thereby and for suspending said frame and stones 30 within the container from the upper portions of the ends thereof.

3. A sharpening stone oiler and support comprising a container having end walls, the upper portions of which are cut away to form openings 35 and notches at the ends thereof, a frame adapted to be positioned in said container, sharpening stones mounted in said frame and combined handles and hangers hinged on horizontal axes to the ends of said frames and adapted to occupy 40 the openings and notches in the end walls of the container to suspend the frame and stones carried thereby within the container or to hold said frames and stones in elevated position within said container.

4. A sharpening stone oiler and support as set forth in claim 3 and the lower edges of the openings formed in the end walls of the container being curved to facilitate the turning movement of the combined handles and hangers when the 50 position of the frame and stones is reversed.

5. A sharpening stone oiler and support as set forth in claim 3 and with notches formed in the sides of said combined handles and hangers for engaging the end walls adjacent the ends of the 55 openings formed therein for maintaining the frame and stones carried thereby in elevated position.

6. In a sharpening stone oiler and support, a frame, a pair of sharpening stones carried by 60 said frame, combined handles and hangers hinged on horizontal axes to the ends of said frame, a container adapted to receive said frame and the stones carried thereby, said container having end walls and the upper portions of which end walls 65 are cut away for the reception of said combined handles and hangers.

7. A sharpening stone oiler and support as set forth in claim 6 and with co-operating means on said end walls and said combined handles and 70 hangers for holding the latter in position, so as to hold said frame and the stones carried thereby in elevated position within said container.

8. A sharpening stone oiler and support comprising a container, a frame adapted to enter 75

5 said container, sharpening stones carried by said frame, plates hinged on horizontal axes to the ends of said frame and hooks on said plates opposite their hinged ends for engaging the ends of the container to suspend the frame and sharpening stones in said container.

9. A sharpening stone oiler and support as set forth in claim 8 and with the ends of the container being notched for the reception of the hooks on said plates.

WILLIAM A. KUHLMAN.
